UNITED STATES PATENT OFFICE.

CHARLES H. TOMLINSON, OF MANSFIELD, OHIO, ASSIGNOR TO THE TOMLINSON COUPLER COMPANY, OF DENVER, COLORADO, A CORPORATION OF SOUTH DAKOTA.

ELECTROPNEUMATIC TRIPLE-VALVE MECHANISM FOR COUPLING SYSTEMS.

1,228,719.

Specification of Letters Patent.

Patented June 5, 1917.

Application filed March 30, 1914. Serial No. 828,157.

To all whom it may concern:

Be it known that I, CHARLES H. TOMLINSON, a citizen of the United States, residing at Mansfield, in the county of Richland and 5 State of Ohio, have invented certain new and useful Improvements in Electropneumatic Triple-Valve Mechanisms for Coupling Systems, of which the following is a specification.

10 The invention relates to valve mechanisms, and the primary object of the invention is to provide an improved triple valve mechanism and the operating means therefor, the latter being adapted to operate or control valve mechanisms of various constructions. Other objects of the invention will appear from the following description of the preferred embodiment of 15 the invention, which is also shown in the drawings and defined more specifically in the claims.

In my application for United States Patent Serial No. 822,802, filed on the 6th day of March, 1914, on an automatic car, air 20 and coupling mechanism, I show a valve constructed in accordance with the principles of the present invention and illustrate the manner in which it is used in my improved system, in which mechanism for 25 automatically coupling two cars, and at the same time coupling the air and electrical devices between the cars, is provided.

The present invention is directed to the construction of the valve itself and its operating means, specifically shown in the drawings, in which Figure 1 is a top plan view and Fig. 2 a view in side elevation of the same, looking at Fig. 1 from the right or from in front of the electrical 30 magnet casing. Fig. 3 is a longitudinal sectional view through the casing containing the valve operating piston and through the electrical magnet casing, with parts in section and parts broken away, while Fig. 4 35 is a sectional view through the valve casing proper and extending through the casing containing piston for operating the valve, this section being taken on a plane approximately at right angles to the view 40 in Fig. 3, with parts of the interior of the casings in section and other parts broken

away or shown in elevation to disclose the details of construction. Fig. 5 is a sectional view taken approximately on lines 5-5 of Figs. 2 and 4. Figs. 6 and 7 are 55 details of an electrical switch connection connected with the valve operating piston. The valve proper is of triple type, in that it is designed to act simultaneously to open or close three different fluid pressure connections. The construction of the valve casing proper is best shown in Figs. 1 and 2, from which it will be seen that two conical casings are provided, as indicated by the reference characters 10 and 11. A central housing is provided, which is indicated by the reference character 12. This member 12 is of an irregular hollow form and is provided with opposed openings designed to take the reduced ends of the conical casings 10 and 11 on diametrically opposite sides thereof. This housing 12 preferably has a depending extension, indicated at 12^a, which is adapted to permit the passage therethrough of a plunger carrying pistons 75 at either end thereof, as shown in Figs. 3 and 4, the plunger being itself designated by the reference character 13 and the pistons as 13^a and 13^b.

To return to the details of the triple valve 80 mechanism proper, it will be seen that the conical shaped casings 10 and 11 are joined to the housing 12, to form a closure therewith by the machine screws 14 passing through lugs 10^a and 11^a and being threaded 85 into the lugs 12^b on the housing 12. This connection is further secured by machine screws 15 passing through the lugs 10^b and 11^b and being threaded into the dependent portion 12^a of the housing. This construction permits the housing 12 and the valve casings 10, 11 to be formed separately and detachably united in the manner described, which is a great convenience in the manufacture and assembling. The conical housings 90 10 and 11 are preferably closed at their opposed outward ends by the hollow screw plugs 15 threaded into their interiors, as illustrated in Fig. 4. The closure members 15 each contain housings for supporting the 95 ends of coil springs 16, which are designed to exert compression between the members

15 and the outer extremities of conical shaped valve members 17 and 18, designed to coöperate with the conical interior portions of the housings 10 and 11, respectively. 5 For coöoperating with the coil springs 16, the enlarged outer extremities of the valve members 17 and 18 are provided with extensions or lugs 17^a and 18^a, respectively, and this construction, it will be seen, will utilize the expansive force of the compression springs 16 to force the conical shaped valves 17 and 18 to their seats within their respective casings 10 and 11 and insure a close working fit at all times, thus automatically taking up any 10 wear or looseness that may result by reason of wear in the operation of these parts. The valve members 17 and 18 are at their reduced and inner ends provided with registering angular openings, as shown, for example, in 15 Fig. 4, being adapted to take the ends of the angular plug 19 connected with lever 20, the upper extremity of which is positioned on the outside of the casing 12, as indicated at 20^a, and being formed into a suitable hand 20 lever by which it may be moved on its pivotal connection in the valve casing by the hand of the operator. The lever 20 is extended below its pivotal connection at 19 with the valve members and in this lower extension is provided with a longitudinal slot 20^b, adapted 25 to coöperate with the pin 13^c, which is secured in a slotted portion 13^e of the plunger 13. The conical valve 18, it will be seen by referring to Fig. 4, is provided with two 30 interior openings in the form of frusta of cones, and these openings may be extended on opposite sides through the walls of the valves 18, as indicated, for example, at 18^b. This opening through the valve 18 may be 35 positioned by rotation of the valve so the valve will cut off the passage laterally of the casing 11 which terminates in the interiorly threaded pipe nipples 11^d on opposite sides of the casing 11, as shown in Figs. 1 and 5. 40 The same construction is provided in the valve member 17, this opening being indicated by the reference character 17^b, and the interiorly threaded pipe nipples in the casing by the reference character 10^d. The valve 45 member 18, in addition to the valve opening 18^b, is provided with a second opening near its outer enlarged extremity which is designated by the reference character 18^d, designed to coöperate with registering openings on opposite sides of the valve casing 11, as indicated by the reference character 11^e, 50 Fig. 1.

Now, it will be seen that the valve members 17 and 18 being connected together, 55 will rotate in unison and are set as illustrated in Figs. 2 and 4, so that they will synchronously open or close the registering openings 10^d and 11^d in the valve casings 10 and 11, and at the same time that the valve member 18 operates to open and

close the openings 11^a through the casing its movement will operate to cause the valve openings 18^d therein to be operated in relation to the opposed openings 11^e of the valve casing 11.

The operation of the device thus partially described may be understood if we assume, as is shown in the application of the valve in my aforesaid application on automatic car, air and electric coupling mechanism, that fluid pressure lines are connected with the nipples 10^d and 11^d and designed to be opened and closed by the synchronous operation of the valves, and that an auxiliary fluid pressure line passes through the valve openings 11^e. Independently of the air and electric means shown in this exemplification of the invention, it will be seen that the valve mechanism may be operated by grasping the handle 20^a and 70 rocking it on its pivotal connection with the valve casing, whereby the valve members 17 and 18 will be synchronously rotated each a partial revolution, and the main valve openings will be synchronously 75 opened and closed, while the auxiliary line passing through the valve opening 18^d and connected with the nipples 11^e of the casing 11 being set at approximately right angles to the openings 17^b and 18^b will be 80 closed when the main valve openings are 85 open and vice versa.

To provide another, and if desirable automatic, means for operating the valve mechanism, the plunger 13 and the pistons 13^a and 13^b thereon, are provided, these co-operating with suitable casings 30 and 31, respectively, the former of which is designed to serve as a cylinder for the piston 13^b and the latter as a cylinder for the piston 13^a. The casing 30 is preferably in 95 detachable form in relation to the central housing 12, being provided with flange portions and adapted to be secured to the central housing 12 by machine screws, as indicated at 32. The end of the casing 30 is closed except for a small opening as indicated at 30^a, threaded and adapted to receive a pipe or duct for supplying fluid 105 pressure to operate the piston 13^b therein. 110 The construction of the cylinder 31 is similar to that of the cylinder 30 just described, except that it is preferably larger in diameter. Machine screws similar to 32 as indicated at 33, Fig. 1, pass through ears cast 115 integrally with the housing 31 for securing the same to the central housing 12.

Preferably, although not necessarily, I cast integrally with the housing 31, as illustrated, an angular extending, depending 125 housing, indicated by the reference character 31^a, which is designed to serve as a covering and support for an electric engine, which is shown in detail in the sectional view Fig. 3. The covering portion 31^a is 130

extended upwardly in a portion of reduced diameter, as indicated at 31^b, across the end of the opening or chamber in the cylinder 31, and is provided with an interior opening disconnected from the interior of the cylinder 31, except for a small port as indicated at 31^c. The upper extremity of the hollow portion 31^b is preferably closed with a screw cap 32^a, having threaded connection with the casing and being designed to support a compression spring 33^a against the upper end of the valve 34, which is designed to close an opening in plug 35. This plug 35 is preferably constructed as shown in Fig. 3, so that it serves to block or close the opening on the interior of the passage of the casing 31^b, except for a small opening extending vertically from top to bottom thereof, and indicated by the reference character 36. For convenience in manufacture an opening extending at right angles to the opening 36 in the plug 35 is provided, the same leading from the vertical opening 36 to the opening 31^c in the end wall of the cylinder 31. The valve 34, while designed to close, under the action of the coil spring 33^a, the upper extremity of the opening 36 in plug 35, is itself controlled by a pin 37 extending vertically through the opening 36 and designed to bear normally against the lower extremity of the valve 34 and against the upper extremity of a second valve 38. The valve 38 is designed to coöperate with a suitable seat at the lower extremity of the vertical opening 36 and is carried upon the upper extremity of a core bar 39. The core-bar 39 is in the form of a brass rod having at its lower extremity an operating member 40 slidably mounted in a housing 41 formed in a closure member secured to the underside of housing 31^a. The closure member 41 is preferably provided with a cylindrical nipple exteriorly threaded and designed to take a corresponding interiorly threaded cap 42, which is perforated, and when in position on the lower extremity of the housing of the electric engine it serves to retain the cup shaped member 40 and the core bar 39 in position, and at the same time permits an outwardly extending stem 43 connected therewith to protrude below the closure member 42, so that if for any reason the valve operating rod 39 should fail to be operated electrically it may be operated by pressing upwardly on the lower extremity of this extension 43. Forty-four is a housing or sleeve threaded in the upper extremity of the casing 31^a and surrounding the plunger 39. At its lower extremity it is preferably threaded for taking a flange washer 45, which latter acts as a support for the usual insulating materials 46, which are designed to support and insulate the coil of the electric magnet indicated by the reference character 48, the same being shown in

section in Fig. 3. The coil of this magnet is supplied with current through the terminal wires 49 and 50 connected to the binding posts 51 and 52, as shown in Figs. 1, 2 and 3. The binding posts 51 and 52 may be of usual or ordinary constructions, as illustrated by the details of the post 51 shown in Fig. 3, which latter, it will be seen, is illustrated as insulated from the housing 31^a and electrically connected with the coil 48, the opposite terminal of which is similarly connected with the binding post 52 and the circuit wire 50. It will be obvious that the current passing from a source of electrical supply, may be used to energize the coil 48, and by operating the armature 40 in a well-known manner, causing it to approach the lower extremity of the coil and the housing 44 on the interior thereof, will lift the valve rod 39 and the valve 38 thereon, closing the lower extremity of the valve opening 36. This movement of the valve 38 will at the same time raise the connecting pin 37, which will lift the valve 34 against the action of spring 33^a and admit fluid pressure through the opening 31^a by way of the passage 36 through the port 31^c behind the piston 13^a, thus operating the piston 13^a, the plunger 13 connected therewith and the valve operating lever 20, which will result in rotating synchronously both the valves 17 and 18 to either their open or closed position, as may be desired by the designer of the valve mechanism.

It will be apparent, however, that my improved valve operating mechanism is designed only to operate the valve to one position by admitting fluid pressure upon the piston 13^a. This provision, I find in practice, is all that is required, for it will be seen by reference to the specific installation of my improved valve mechanism, as shown in my said application on automatic car, air and electric coupling system, that I utilize the electrically operated valve mechanism just described only for the purpose of operating the plunger and the main valves thereby to the closed position, while these parts are shown, for example in Fig. 3, in the open position prior to their operation to the closed position. For operating the plunger 13 and the piston 13^b thereon and the valve mechanism controlled thereby to the open position or the position shown, for example in Fig. 3, fluid pressure is admitted in any desired manner from some part of the system through the opening 30^a. One manner of connecting up the device with the fluid pressure is illustrated in my prior application already referred to. In 125 the casing 31^b is shown a vent 31^c, which, it will be seen, permits the operation of the piston 13^a when fluid pressure is admitted into the cylinder 30 behind the piston 13^b, for the fluid within the cylinder 130

31 may pass through the port 31^c and downwardly past the open valve 38 to the atmosphere through the vent 31^e.

An important feature of my invention is the construction of the piston operating cylinders 30 and 31 of different sizes, the cylinder 31 being of larger interior diameter and, consequently, taking a piston of larger diameter, as indicated at 13^a, Fig. 3, than the cylinder 30 and its corresponding piston 13^b. Although means for operating the pistons 13^a and 13^b by hand is provided, the preferred manner of operating my valve mechanism is by fluid pressure from a combined reservoir line and brake line system, as shown and described in my application on automatic car, air, and electric coupler system already referred to. In order to operate the pistons 13^a and 13^b from fluid pressure in a system of this character and since the pressure will be upon the cylinder 30 constantly, as no provision is made for venting that cylinder or the pipe line leading to it, it is desirable that the area of the piston 13^a, which is the off cylinder, shall be larger in cross sectional area than the area of the piston 13^b. This will enable pressure admitted through valve 34 and port 31^c from a source of pressure to operate the piston 13^a and carry with it the connected piston 13^b against pressure from the same source within the cylinder 30. Therefore, when the operating valve 13 has been moved to the on position carrying the main valve to the on or open position, as shown, for example, in Fig. 3, the pressure, applied to the piston 13^a will be effective to shift the valve to the closed position against a like pressure within the smaller cylinder 30, provided, of course, that the difference in size between the cylinders 31 and 30 and their corresponding pistons is made sufficient for the purpose, as illustrated in Figs. 1 and 3.

On the plunger 13 is secured an insulated member 60, adapted to coöperate with spring arm 51^a to cause it to contact with the spring arm 52^a when the plunger 13 is in a position for example shown in Fig. 3, which is the open position of the valves, and will close an electrical circuit through the spring contacts 51^a and 52^a and suitable binding posts, as indicated at 53 and 54, leading to the circuit wires 55 and 56, which may be utilized as portions of the electric circuit for signal lights to indicate when the valve is in its open or closed position.

In the valve member 18 an auxiliary opening 18^e is provided, as shown in Fig. 5, which will, upon the operation of the valve member 18, be caused to register with a vent 11^e leading to the atmosphere. This feature of construction will permit a venting of portions of the fluid pressure pipe system when the valve is closed, if desired.

In order that the invention may be understood, the preferred embodiment has been shown and described, but it is not desired to be limited to the details, for it will be apparent that a person skilled in the art may 70 make many modifications without departing from the purpose and spirit of the invention.

I claim:

1. Valve mechanism for car coupler systems and the like comprising a plurality of operatively connected valve members, a housing for said members, two cylinders opening on the interior of said housing and providing opposed openings for receiving each a piston on a common plunger, means for operating said valve members from said plunger, connections for admitting fluid pressure for operating each of the pistons on said plunger, and means for controlling the fluid-pressure connections to one of the pistons on said plunger comprising a valve, elastic means for seating said valve, and an electrically operated device for unseating said valve to admit fluid pressure into the cylinder of said piston.

2. Valve mechanism for car coupler systems and the like, comprising a valve housing or casing consisting of a central compartment with two diametrically opposed 95 housings or casings in the form of frusta of cones secured to the said central housing with their ends of smallest diameter engaging the central housing, valve members of the general form of frusta of cones within 100 the casings or housings, means for closing the outer extremities of said casings or housings, elastic means interposed between said last-mentioned means and the said valve members for holding them in their normal seated position, and common means in the central housing for operating the said valve members.

3. Valve mechanism for car coupler systems and the like, comprising a valve housing or casing consisting of a central compartment with two diametrically opposed 110 housings or casings in the form of frusta of cones secured to the said central housing with their ends of smallest diameter engaging the central housing, valve members of the general form of frusta of cones within 115 the casings or housings, means for closing the outer extremities of said casings or housings, elastic means interposed between said last-mentioned means and the said valve members for holding them in their normal seated position, common means in the central housing for operating the said valve members, comprising a lever engaging both 120 said valve members, and a pneumatically-operated reciprocating plunger operatively connected with said lever.

4. In a valve mechanism for car coupler systems, and the like, the combination with 130

a central casing, of two cylinders of unequal diameters located on the same axial line with each other on diametrically opposite sides of said central casing, conical valve chambers in communication with said central casing and extending on diametrically opposite sides thereof at approximately right angles to said cylinders, respective valve members in said valve chambers being 5 adapted to control the passage of fluids through said chambers, respective pistons in said cylinders of unequal diameters and co-operating therewith, a rigid connection between said pistons, and an operative connection 10 between said piston connection and said valve members for operating the latter.

5. In a valve mechanism for car coupler systems, and the like, the combination with a central casing, of two cylinders of unequal 20 diameters located on the same axial line with each other on diametrically opposite sides of said central casing, valve chambers in the form of frusta of cones in communication with said central casing and extending on diametrically opposite sides thereof at approximately right angles to said cylinders, respective perforated valve members in said valve chambers being adapted to control passage of fluid through said chambers, respective pistons in said cylinders of unequal 25 diameters and co-operating therewith, a rigid piston rod connecting said pistons, and an operative connection between said piston rod and said valve members for operating the 30 latter.

6. In a valve mechanism for car coupler systems and the like, the combination with a central casing, of two cylinders of unequal diameters located on the same axial line with 40 each other on diametrically opposite sides of said central casing, valve chambers in the form of frusta of cones in communication with said central casing and extending on diametrically opposite sides thereof at approximately right angles to said cylinders, respective perforated valve members in said valve chambers being adapted to control the 45 passage of fluid through said chambers, respective pistons in said cylinders of unequal diameters co-operating with said cylinders, a rigid piston rod connecting said pistons, operative connections between said piston rod and said valve members for operating the latter when said piston rod is operated, 50 means for admitting fluid pressure into said cylinders behind said pistons to operate the latter, and means for operating said valves by hand, at the will of the operator.

7. In a valve mechanism for car coupler systems, and the like, the combination with a central casing, of two cylinders of unequal diameters located on the same axial line with each other on diametrically opposite sides of said central casing, valve chambers in the 55 form of frusta of cones in communication

with said central casing and extending on diametrically opposite sides thereof at approximately right angles to said cylinders, respective perforated valve members in said chambers, respective pistons in said cylinders of unequal diameters and co-operating therewith, a rigid piston rod connecting said pistons, operative connections between said piston rod and said valve members for operating the latter when said piston rod is operated, means for admitting fluid pressure into said cylinders behind said pistons to operate the latter, and means for operating said piston rod and said valves at the will of the operator. 70

8. In a valve mechanism for car coupler systems, and the like, the combination with a central casing, of two cylinders of unequal diameters located on the same axial line with each other on diametrically opposite sides of said central casing, conical valve chambers in communication with said central casing and extending on diametrically opposite sides thereof at approximately right angles to said cylinders, respective perforated valve members in said chambers being adapted to control the passage of fluids through said chambers, respective pistons in said cylinders of unequal diameters and co-operating with said cylinders, a rigid connection between said pistons, an operative connection between said piston connection and said valve members for operating the latter, a valve controlled connection for admitting fluid pressure to the cylinder of larger diameter, and an electrically operated device for moving the valve of said valve controlled connection. 85 90 95 100

9. In a valve mechanism for car coupler systems, the combination with a central casing, of two cylinders of unequal diameters located on the same axial line with each other, on diametrically opposite sides of said central casing, conical valve chambers in communication with said central casing and extending on diametrically opposite sides thereof at approximately right angles to said cylinders, respective perforated valve members in said valve chambers being adapted to control the passage of fluids through said chambers, respective pistons in said cylinders being rigidly connected to operate synchronously, connections between said valves and said pistons for operating them upon the operation of the pistons, a metallic 105 housing adjacent the larger one of said cylinders, there being a fluid inlet port communicating between the interior of said housing and the interior of said cylinder, and a port leading to the atmosphere 110 through the wall of said housing and communicating with said inlet port, means for supplying fluid pressure to the interior of the housing, and a valve controlled device 115 for admitting fluid pressure through the in- 120 125 130

let port into the cylinder and closing the passage to the atmosphere and for closing the passage to the inlet port and opening the passage therefrom to the port to the atmosphere at the will of the operator.

5 In testimony whereof I have signed my name to this specification, in the presence

of two subscribing witnesses, on this 24th day of March, A. D. 1914.

CHARLES H. TOMLINSON.
